UNITED STATES PATENT OFFICE

172,389

NURSERY LAMP

Robert Goldman and Roy R. Nemzer, South Hempstead, N. Y., assignors to Bo-Low Lamp Corp., Brooklyn, N. Y., a corporation of New York

Application December 23, 1953, Serial No. 28,188

Term of patent 7 years

(Cl. D48—20)

To all whom it may concern:

Be it known that we, Robert Goldman and Roy R. Nemzer, both citizens of the United States and residents of South Hempstead, in the county of Nassau, State of New York, having invented a new, original, and ornamental Design for a Nursery Lamp, of which the following is a specification, reference being had to the accompanying drawing, forming a part thereof, and of which:

Fig. 1 is a front elevational view of a nursery lamp showing our new design.

Fig. 2 is a right side elevational view thereof.
Fig. 3 is a left side elevational view thereof,
and

Fig. 4 is a top plan view thereof.

We claim:

The ornamental design for a nursery lamp, as shown.
